PORTABLE STOVE

Lou H. Luedtke, Muncie, Ind.

Application March 1, 1939, Serial No. 259,252

3 Claims. (Cl. 248—165)

This invention relates to improvements in portable stoves,—by the word stove being meant a knock down construction which when not in use occupies relatively small space, but which is capable of being conveniently transported and of being readily set up at the place desired.

Advantages desired in a device of this kind are that it may be substantial and dependable, and may readily lend itself to the accommodation of a grill for any of various requirements; that it may be relatively light in weight and economical of manufacture, and that it may be conveniently used as camping outfit, and also as equipment in the shop, factory or household.

15 My improved table construction, consisting as it does, of a carrying case, and of unitary parts contained therein which are of form and structure to be easily removed, and then fitted and fastened together I have, in illustrating my invention, pictured the several parts individually, and I have shown the invention as knocked down and in the status for being transported. Also, the invention is shown set up and in readiness for use.

20 The general objects of my invention, and also more specific aims thereof, as will presently appear, are accomplished by, and the invention is embodied in the new construction, combination and arrangement of parts illustrated in the accompanying drawing and described in the following specification. The several parts of the invention are identified by suitable characters of reference applied to them in the different views in the drawing.

25 Figure 1 is a front view of my improved portable stove construction, as it appears in readiness for use.

Figure 2 is a top plan view taken in the direction of arrow 2 in Figure 1.

30 Figure 3 is a vertical central cross section view taken on the line 3—3, and in the direction of arrow 3 in Figure 2.

Figure 4 is a sectional top plan view taken on the line 4—4 and in the direction of arrow 4 in Figure 1.

35 Figure 5 is a side view of the carrying case, a portion of the side wall thereof being broken away; and which said casing, when the shell cap thereof is in transposed and inverted position as indicated in Figure 1, constitutes a central column upon which the top portion of the frame construction is retained.

40 Figure 6 is a side view of one of the two cross bars which are adapted to be reposed on the top

of the casing when the latter is in the position as in Figure 1.

Figure 7 is a side view of the other one of said cross bars.

Figure 8 is a top plan view of one of two opposed side rails.

Figure 9 is a top plan view of the other one of two opposed side rails.

Figure 10 is a detached view of one of the post and strut assemblies.

Figure 11 is a detached view of one of the tension rods.

Figure 12 is a perspective view of preferred form of arrangement of criss-cross members constituting a grill, intended for the accommodation of electric heating units.

An important feature of this invention being that the construction is knock down—that is to say, the several parts are capable of being easily disassembled, and then placed in order wherein they occupy relatively small space and may be retained in a carrying case, I will describe each of the parts in detail and as detached.

For a table of twenty one inches in width, the hollow body structure which I designate as the casing A may be cylindrical in cross section, and about eight inches in diameter. This casing is closed at one end. At the rim portion of the open end of said casing are spaced notches B. A cap shell C which may be made of sheet metal is removably held in position closing the casing, as by set screws D. In its position removed, it is made fast by the same set screws D, to the closed end of the casing whereby it constitutes a base structure (as shown in Figure 1) and to which certain parts are connected, as will be presently pointed out. Embodied with said cap shell are four spaced brackets C1, and each having a radially directed socket E, and above said socket is an eye F.

Cross bars G and H, as shown in Figures 6 and 7, are provided with central recesses I and end recesses J respectively, whereby when they are in crossed position their top surfaces are at a common plane. Shallow end recesses K are adapted to receive the side rails presently to be referred to. Recesses L being engaged with the recesses B of the casing, these cross bars are suitably retained in their positions.

Opposed side rails of angle iron, are of right and left formation. Each rail M of one pair, has at each end of its vertical leg, a threaded stud N and nut O; and near the ends of the horizontal legs are the holes M' and M'. Each rail P of the other pair of side rails has each end of its horizontal leg cut away, and at each end of its verti-

cal leg is provided a threaded stud Q and a nut R. A transverse shallow recess M2 and P2 centrally of the horizontal leg of each of the aforesaid rails constitutes a seating by which these 5 rails are readily centered on the ends of the cross bars presently to be referred to.

Corner uprights, and which I designate as post and strut assemblies, are similar in construction and function. Each consists of an angle iron S of suitably light weight, each leg of which at 10 its top is provided with a hole T in which is to be received a stud of the aforesaid side rail. The function of another hole T' provided in said post will be presently referred to. At S' the post is twisted so that its lower portion is inclined 15 at a right angle to the axis of the brackets C1. Pivotally connected, as at U1 to the bottom of the post, is a strut member which consists of an angle iron U. A portion of the free end of 20 this angle iron is cut away thereby constituting the end portion as a shank or nose V and which is adapted to be inserted in and retained in the socket E of the said base bracket.

Each of similar tension members consists of 25 a light divided rod, the sections W thereof being joined by a turnbuckle X, and the ends of said sections embodying hooks W1 and W2.

My improved portable stove or table construction as received by the user is in the knocked 30 down status, the several parts thereof being retained in their disassembled status, within the casing A as shown in Figure 5; the latter being closed by the cap shell C. The outfit in this status may be conveniently transported, and it 35 occupies relatively small space. Whereas the diameter of the casing A is shown as about eight inches in diameter, this dimension may be varied according to the sizes of the parts as they may be varied according to design.

40 Installing or setting up the stove for actual use, follows;

The cap shell is transferred from the position as in Figure 5, to the closed end of the casing, and in which latter position it appears as in 45 Figure 1, the set screws D having been tightened and the said shell now constituting a substantial base structure to which the several parts presently to be referred to are connected. After the removing from the casing of all of the said parts, 50 the casing is now disposed in upright position as in Figure 1. The cross bars G and H are now disposed in place in their dovetailed right-angle relation (see Figure 2), and at repose in the recesses B of the top of the casing, and the recesses 55 L retaining them against dislodgement. Struts U and U of two of the post-strut assemblies, are swung to right angle position and their shanks V are inserted into the sockets E and E of the cap shell, and there they are secured by the set screws E1 and E1. The posts are then swung to 60 upright position and are made fast to the ends of the side rail M by engaging the studs N and by being secured by the nuts O. The same procedure then follows with the other two post strut 65 assemblies.

Now the side rails M and M are drawn toward each other, same being centered and spaced on the recesses K in the ends of the cross bar H. Side rails P and P are then placed in positions 70 on the ends of cross bar G, the nuts R and R binding said rails to the tops of the posts. The sections W and W of the tension rods have their hook ends W1 and W2 connected at the apertures M' of the side rails M M and the eyes F of the base brackets, respectively. By operating

the turnbuckles X the side rails are drawn to tight engagement with the ends of the cross bars G and H, and the said cross bars in turn, are drawn to and are held in tenacious engagement with the top of the said casing. By the structure thus constituted, the frame in which the grill is to be retained is strong and substantial and it is provided with the solid central support which is very desirable. The structure thus formed is capable of being constituted of members which 10 are of sheet steel pressed into form affording the desired formation in cross section, and whereby the structure complete is, while light in weight, strong and durable. Being free from cross connections between the body portions of the posts 15 it affords foot room so much desired when working about a table structure of this kind. The construction as an entirety may be anchored by the use of bolts or pins at the holes U2 in the struts U. Or it may be fastened to the wall by 20 use of screws or nails at the holes T1 in the posts S. The frame lends itself to accommodating a deck plate or structure of any desired form; and especially of a grill constituted as shown in Figure 12, and consisting of light steel members T 25 shaped in cross section, dovetailed and so interconnected that when disposed in place they are automatically retained, and wherein suitable gaps for the reception and use of electric heating units or the like, are provided.

Whereas the features of construction, in general and in detail, are those which I consider preferable for carrying my invention into effect, I wish it to be understood that minor changes and modifications may be made without departing 30 from the spirit or principle of my invention, and that the invention shall be construed as of the full scope as defined in the appended claims.

What I claim as my invention, is—

1. A portable stove construction consisting of 40 a hollow casing closed at one end, a cap shell adapted to constitute a closure for the open end, and which is removable and is adapted to be transferred to and made fast at the closed end of said casing to constitute a base structure 45 thereat, cross bars carried by and which extend beyond the sides of the top end of the casing, parts combined with the said base structure and the said cross bars to constitute a deck retainer, the said parts being demountably interrelated 50 and being adapted to be disassembled and contained within the said casing.

2. A portable structure of the kind described, comprising a hollow casing closed at one end, a cap shell adapted to constitute a closure for the 55 open end, and which is removable and is adapted to be transferred to and made fast at the closed end of said casing to constitute a base structure thereat, diametric interengaged cross bars carried by and which extend beyond the sides of 60 the top end of the said casing, side rails arranged in rectangular formation and supported by said cross bars in predetermined position, and tension members interconnecting the side-rails and the said base structure, to draw the said side 65 rails, the said cross bars, and the said casing, into united relation.

3. A portable structure of the kind described, comprising a hollow casing closed at one end, a cap shell adapted to constitute a closure for 70 the open end and which is transferable to and is adapted to be made fast at the closed end of said casing to constitute a base structure therefor, cross bars carried by and which extend beyond the sides of the top or open end of said 75

- casing, side rails to rest on the ends of the said cross bars, post members extending downwardly from the ends of said side rails, struts extending from the bottoms of said post members and to interlocked engagement with the said base structure, tension rods interconnecting the side rails

and the said base structure, and means to adjust said rods whereby upon tightening same, the side rails, cross bars and casing are drawn to and are held securely in united relation.

5

LOU H. LUEDTKE.
